T. H. McCOMSEY

ELECTRIC PAD

Filed April 6, 1926

Inventor
Thomas H. McComsey
By
R. S. Barry
Attorney.

UNITED STATES PATENT OFFICE.

THOMAS H. MCCOMSEY, OF LOS ANGELES, CALIFORNIA.

ELECTRIC PAD.

Application filed April 6, 1926. Serial No. 160,036.

This invention relates to improvements in electrically heated pads and more particularly to pads for therapeutical treatment of the human body.

5 Among the objects of my invention is to provide an anatomically shaped pad and heat unit whereby the pad, as a whole, will closely conform to the body and the heat therefrom be uniformly distributed and applied over the body.

10 Another object is to provide a heat unit comprising a plurality of coils of substantially oblong shapes and having rounded ends and a single coil of substantially U-shape, all formed from a continuous length of wire and relatively fabricated as by ribbons or tapes to comprise a flexible and anatomy conforming heat unit for treatment of the human body particularly about the neck 15 and upper body.

15 My improvements consist in the novel construction, arrangement and combination of parts as hereinafter fully, clearly and concisely described, definitely pointed out in my 20 claims and illustrated by the accompanying drawing (1 sheet) in which:—

Fig. 1 is a view in perspective of a device constructed in accordance with my invention;

25 Fig. 2 is an elevation with one of the pad sections removed and shows the relative disposition of the several coils of the heat unit and control therefor;

Fig. 3 is a wiring diagram;

30 Fig. 4 is an enlarged transverse section elevation, taken on the line 4—4 of Fig. 2 showing the fabrication of the several coils.

35 Referring more specifically to the drawing, the numerals 10 and 11 designate the front and back sections of the pad, or heat unit envelope, which in its finished state, has a seam uniting the two sections at their 40 margins for the complete enveloping and retention of the heat unit and by preference such pad sections are made of woolen cloth.

45 The heat unit comprises one or more coils 12 of oblong contour having substantially straight, parallel sides and rounded ends and built up of a continuous length of wire, 50 such as insulated magnet wire of approximately 21 gage and of single strand.

55 This shaping of the coil affords maximum flexibility and adapts the coil as a whole to conform readily to the anatomical part to be treated and, such shaping of the coil obviates

sharp angles in the wires which tend to breakage.

Associated with the coil or coils, just recited, is a similarly built up coil 13, whose major lengths are arcuate for close fitment 60 about the neck and shoulders of the users.

In the single length of wire entering into and forming the coils 12 and 13, I provide interconnecting, loose lengths 14, providing flexure between the various coils and I further provide structure bonds 15 between the various coils in the form of flexible ribbons, or tapes extending between and uniting the "lengths" of the coils by tying or knotting between the coils as best shown in Figs. 2 70 and 4. The ends of the wire are connected in a connector with a source of electrical supply, such as the plug 16, shown in Figs. 1 and 3.

For the control of energy flow through 75 the various coils I provide a control 17, which by preference is a thermostatic switch (of any approved construction) which maintains uniformity of action and prevents overheating.

80 By further preference, and as shown in Figs. 2 and 3, I provide two of such control devices, whereby the pad may be used with high or low voltage circuits and by further preference such controls are incorporated 85 within the pad body or envelope as shown.

I claim:—

1. In a device of the class described, a heating unit comprising a plurality of coils constructed of a single length of wire and 90 each having spaced parallel sides and rounded ends, said wire extending loosely between the coils, a fabric envelope enclosing said coils and a flexible structure bond independent of said fabric envelope between 95 the coils.

2. A device of the class described comprising a plurality of coils having straight parallel sides and rounded ends, a single coil having arcuate sides and rounded ends, flexible 100 electrical connections between the various coils, a flexible structure bond between the lengths of the various coils, a textile envelope enclosing said bond and coils, and a thermostatic control for the energy flow 105 through the coils.

3. A device of the class described comprising a body portion, containing a plurality of transversely extending coils having straight parallel sides and rounded ends; in combi- 110

nation with a neck portion having a coil with an arcuate side portion and rounded ends, flexible electric connections between the various coils, a fabric envelope enclosing all 5 of said coils, said arcuate coils having their convexity directed towards the other coils, a pair of tape bonds one at each side of the mid-length of said arcuate coil and con-

nected to the adjacent straight coil, and tape bonds connecting together the straight 10 leads of the other coils, said tape bonds being independent of the structure of said fabric envelope.

In testimony whereof, I have affixed my signature.

THOMAS H. McCOMSEY.
